TURBINE

Herman Danel, Argenteuil, France

Application April 1, 1933, Serial No. 664,016
In Germany April 2, 1932

2 Claims. (Cl. 253—50)

This invention relates to a turbine wherein steam or any other fluid may be utilized on long passages and used up to do work, instead of letting it flow out in free expansion, as hitherto practiced.

Such work is done by causing steam to pass through a plurality of perforated plates or grates, removable or not removable. The accompanying drawings illustrate the progress of this steam traversing all these grates and more than three millions of perforations in the large types of turbines.

Figures 1 and 1a show two different grates with perforations in staggered arrangement.

Figures 2, 3, and 4 are perspective views of different rotors of such a turbine.

Figure 5 is a front view of a stator unit mounted in a casing and disclosing the way the plates are arranged and distributed in the channels.

Figure 6 is a plan view of the stator showing in dotted lines derivation passageways causing steam to pass from one drum to another.

Figure 7 is a perspective view of the whole arrangement of the turbine.

This turbine is essentially constituted by a rotor comprising a series of drums (Figures 2, 3, and 4), on the periphery of which channels 2 are arranged adapted to receive steam. These channels are provided with perforated plates 2 dividing the steam into an infinite number of jets, as would be the case with a great number of superposed spray-cones. The perforated parts of the plates do not lie on the same line, but are staggered.

Each one of these jets is directed on the imperforate portions of all the grates which are struck by the front, the action being wholly perpendicular to the central axis and without any oblique or lateral pressure. These grates are so arranged as to allow the perforations of one grate to alternate with the perforations of the following. In other words, the imperforate portions of one grate should correspond with the perforations of the preceding grate. The perforations are thus in staggered relation, causing the steam to spray on the quadrilateral surfaces spacing them apart, and as the steam must traverse an unlimited number of "squares" or "cross-roads" it may thus be used up to the utmost limit of its main zones of elasticity, being forced to always remain under the action of a resistance, avoiding eddying and braking effects.

These plates or grates are as near one another as possible and may be arranged in groups, in such a manner as to leave free spaces to facilitate

the admission of steam which may be effected through one or more nozzles. These grates may also have a continuous and regular succession, i. e. they may be distributed on the periphery of the drums. They may also be arranged in steps, i. e. unequally dimensioned on the same drum, or they may be all alike.

One of the features of this turbine lies in the shape of the passageways 9 arranged to cause steam to pass alternatively from one drum to the other, with great facility, and to serve at the same time as a support therefor. These passageways 9 leave and arrive tangentially to the drums and are of a cross-section substantially equal to the latter.

Another feature of the invention is the perforation of the grates which enables the steam to have a speed much greater than that of the rotor, whatever the pressure may be, and to work at a great range on great surfaces.

The perforations may have various dimensions and shapes: circular, square, lozenge, octagonal, small or great, short or elongated, also vertical horizontal or diagonal.

The rotor is surrounded by a stator 10 in the dome of which the passageways 9 are provided which remove completely the steam at the outflow from each of the drums of which it achieves a nearly complete revolution, and as the device may be applied to all dimensions, it is possible to modify at will the diameter of the turbine. With the aid of a great lever (radius) which may have 3, 4, 5 meters and more, and with grates having each up to 50 dm² and more, a working ability may be obtained which is considerably greater than all those attained up to now. The drums and the passageways may also be modified at will, as shown in Figures 2, 3 and 4: viz regular (Figure 2), with increasing diameter (Figure 3), widening with equal diameter (Figure 4).

From above description, it is seen that the inventor provides a means to cause a fluid, for instance steam, to work on a much greater circuit and on greater surfaces than it does at present. It may be used at all pressures, from the lowest to the highest, keeping a striking and penetrating power up to the last perforation, even after a long passage, as its speed is always independent of that of the rotor which is checked by the work which it has to furnish. This indicates that its efficiency will thus be considerably increased.

This application is a continuation in part of my copending application, Serial No. 542,933, filed June 8, 1931.

I claim:—

1. A steam turbine comprising a fixed stator and a rotatable rotor, the rotor being divided into a plurality of connected drums, each drum having a channel in the periphery thereof, a plurality of removable perforated plates radially mounted in each channel and positioned close together, the perforations of each plate being substantially equal to one-half of the surface of each plate, and the perforations of one plate being staggered with respect to the perforations in adjacent plates, the perforated plates in each channel being arranged in circumferentially spaced groups and the plates in each group being positioned close together.
2. A steam turbine comprising a fixed stator and a rotatable rotor, the rotor being divided into a plurality of connected drums, each drum

having a channel in the periphery thereof, a plurality of removable perforated plates radially mounted in each channel and positioned close together, the perforations of each plate being substantially equal to one-half of the surface of each plate, and the perforations of one plate being staggered with respect to the perforations in the adjacent plates, the perforated plates in each channel being arranged in circumferentially spaced groups and the plates in each group being positioned close together, said stator having a plurality of passageways for connecting the channel in the periphery of one drum with those in adjacent drums, said passageways being of cross-section substantially equal to the channels in the drums, and being positioned for introducing and discharging steam tangentially to each drum.

HERMAN DANIEL.
